UNITED STATES PATENT OFFICE.

JOHN NEIL, OF NEW YORK, N. Y., ASSIGNOR TO THE BIGELOW CARPET COMPANY, OF CLINTON, MASSACHUSETTS.

DESIGN FOR A CARPET.

SPECIFICATION forming part of Design No. 12,441, dated August 30, 1881.

Application filed July 29, 1881. Term of patent 3½ years.

To all whom it may concern:

Be it known that I, JOHN NEIL, of New York, county and State of New York, have invented a new and original Design for Carpets, of which

5 the following is a specification.

This invention relates to a new and original design for carpets and similar fabrics; and it consists in the novel grouping and configuration of figures hereinafter more fully described.

10 The accompanying photograph illustrates a face view of a carpet having my new design.

This carpet is divided into two longitudinal parallel portions, A and B. The portion A, occupying the larger part of the space, has, where 15 it touches the portion B, a border, m, and at the opposite side a narrow border, a, and next to the same a broader border, c, within which are series of rosettes b. The space between the borders c and m is a checkered field, baving upon it the figure C and the figure g. The checkered field is indicated by the letters i, and is composed of alternate longitudinal and transverse lines.

The figure C consists of a small circular rosette, d, bearing a larger rosette-like flower, e, with leaves growing out of the junction of d and e. From the flower e projects a spear-shaped ornament, f, into the border m. g is a flower-like figure having a spray, h, projecting into the border m, said spray carrying leaves j within said border m. Some of the leaves

j that extend from the spray h reach even to the part B of the carpet. The border m has ornamental dots n and groundwork, as indicated.

35 The part B of the carpet consists of four stripes, o r t s, all of which are ornamented in the manner indicated, to wit: The stripe o has zigzag outline, and near the same ornamental rosettes and geometrical figures. The stripe r contains a string of clover-leaves. The border t is made up of small rosettes, and the stripe s is ornamented with alternate longitudinal and transverse lines to give it a checkered appearance.

45 I claim—

1. The design for carpets, consisting of the figures B, o, r, t, and s, substantially as shown.
2. The design for carpets, consisting of the figures A, m, a, and c, substantially as shown. 50
3. The design for carpets, consisting of the figures C, d, e, and f, substantially as shown.
4. The design for carpets, consisting of the figures g, h, and j, substantially as shown.
5. The design for carpets, consisting of the figures A, B, C, a, c, b, d, e, f, g, h, i, j, m, n, o, p, r, and s, substantially as shown.

55 JOHN NEIL.
